UNITED STATES PATENT OFFICE.

EDMUND MORRIS, OF MICHIGAN CITY, INDIANA.

DESIGN FOR CANE FABRIC.

SPECIFICATION forming part of Design No. 25,677, dated June 23, 1896.

Application filed May 2, 1896. Serial No. 590,036. Term of patent 7 years.

To all whom it may concern:

Be it known that I, EDMUND MORRIS, a citizen of the United States, residing at Michigan City, in the county of La Porte and State of Indiana, have invented and produced a new and original Design for Cane Fabric, of which the following is a specification, reference being had to the accompanying drawing, forming part hereof, which shows a piece of cane fabric designed according to my invention.

The design consists of the parallel stripes *a*, each made up of short lengths or sections *x*, and having octagonal figures *y*, and the similar transversely-arranged stripes *b*, which with the stripes *a* produce on the fabric the squares *X*, within each of which are arranged a number of octagonal figures.

The leading feature of my design is the arrangement of the intersecting stripes *a* and *b*, each containing octagonal figures and producing the squares *X*, having a number of octagonal figures, substantially as shown in the accompanying drawing.

I claim—

The design for a cane fabric, substantially as herein shown and described.

In testimony whereof I have hereunto subscribed my name.

EDMUND MORRIS.
